UNITED STATES PATENT OFFICE.

NATHANIEL B. LEAMAN, OF LITITZ, PENNSYLVANIA.

BOX-FASTENER.

SPECIFICATION forming part of Letters Patent No. 689,205, dated December 17, 1901.

Application filed September 12, 1901. Serial No. 75,223. (No model.)

To all whom it may concern:

Be it known that I, NATHANIEL B. LEAMAN, a citizen of the United States, residing at Lititz, in the county of Lancaster and State of Pennsylvania, have invented new and useful Improvements in Box-Lid Fasteners, of which the following is a specification.

This invention relates to boxes, and more especially to a lid-fastener therefor, and has 10 for its object to provide simple and efficient means of this character whereby the lid can be securely held closed no matter how roughly the box may be handled and this without the use of nails or screws, and the lid may be 15 quickly applied to and removed from a box and with very slight effort.

The improved box, which may be used for receiving different articles, consists of a body and a lid or cover therefor, the lid having a 20 plurality of projections at one side adapted to be suitably supported by one side of the body and a plurality of projections at the opposite side thereof to engage under the shoulders of spring-catches carried by the adjacent side of the box, and by pushing these 25 catches outward by the thumbs or otherwise they will be carried free of the co-operating projections, whereby the lid can be raised. These projections consist in the present case 30 of the ends of pins or rods extending across the under side of the lid or cover, the pins or rods serving to stiffen or strengthen the lid or cover.

The invention is clearly represented in the 35 accompanying drawings, forming a part of this specification, in which—

Figure 1 is a plan view of the box. Fig. 2 is a similar view of the same with the lid or cover removed. Fig. 3 is an under side view 40 of the lid. Fig. 4 is a cross-section of the box.

Like characters refer to like parts in all the figures of the drawings.

It will be understood that I use the term "box" in its broad sense to include within 45 its scope receptacles of any kind for containing merchandise or other articles, and said box may be made of any suitable material, shape, and size.

The box illustrated is of rectangular form 50 and is constructed of wood, its body being denoted by 5 and the lid by 6, two of the sides

of the body being made higher than the other two, so as to receive between them the lid, which rests on the shorter sides.

The lid 6 has on its under side, near the opposite ends thereof, the transversely-disposed cleats or cross-pieces 7, which are a trifle shorter than the width of the cover and the outer faces of which engage the inner faces of the short sides of the box-body to thereby prevent endwise motion of the lid.

A plurality of posts, as 8, (four being shown,) are suitably secured in the box at the corners thereof, and they strengthen the box, and their tops are beveled to receive the correspondingly-beveled ends of the cleats 7.

Between what are shown as the rear posts and the box-body are arranged plates, as 9, the upper ends of which extend above the upper beveled edges of said posts, said extended ends being perforated, as at 9', to receive the rear ends of the projecting portions of the parallel pins or rods 10. The cleats or cross-pieces 7 are grooved longitudinally to receive these pins or rods, which serve to stiffen the lid or cover and the ends of which project beyond the cleats, the rear projections, as just set forth, being inserted in the holes or perforations in the plates 9. The forward projections of said pins are adapted to engage under the shoulders 12' of the spring-catches 12. These spring-catches are situated between the forward posts 8 and the box-body, the posts being cut away near their upper ends to produce a space in which said 85 spring-catches can work back and forth. Said spring-catches are preferably made of light metal, and the shoulders may be formed by bending the metal on itself, and said shoulders have their inner faces beveled, which 90 may be produced by bending the same at the proper angle relatively to the bodies of the catches.

The under side of the lid, at the inner edge thereof, is recessed, as at 13, to receive the 95 upper ends of the plates 9 when the lid or cover is on.

To apply the lid, the inner projecting ends of the pins or rods 10 will be inserted in the perforations 9', and the forward end of the 100 lid will be lowered until the forward projecting portions of said pins strike the shoulders

of the spring-catches 12. Then by exerting a slight downward pressure on the box the spring-catches 12 will be sprung outward, and when the forward ends of the pins 10 pass below the beveled shoulders the catches will snap inward and the shoulders 12' will engage over said forward ends to hold the lid or cover 6 down.

The forward edge of the lid or cover is notched, as at 14, the presence of the notches affording ready access to the free ends of the catches 12 for disengaging their shoulders from the forward ends of the pins 10 to raise the cover. When the operation just pointed out has been concluded, the rear ends of the pins 10 can be slipped out of the perforations and the lid thereby wholly disconnected from the body.

To facilitate the action of the pins 10, their opposite ends are sharpened.

The box, it will be evident, is strong. Its lid can be quickly and easily applied and removed and when in place is held firmly against removal by rough handling and without the necessity of employing nails, screws, or equivalent fastening devices. Labor and time are thereby saved, and the lid may be put on and taken off as desired without the use of tools and without injuring the box.

The invention, of course, may be modified within the scope of the appended claims.

Having described the invention, I claim—

1. In a box, a body, a lid for the body, posts on the body at the corners thereof, plates between the posts at one side of the body and said body, having perforations, spring-catches between the opposite posts and the body, and projections upon opposite sides of the lid, certain of which are adapted to enter said perfora-

tions and the remainder of which are engaged by said catches. 40

2. In a box, a body and a lid, posts in the body, the upper ends of which are beveled, cleats extending across the under side of the box, having their ends beveled to correspond with, and to engage, the other beveled portions, pins passing entirely through and beyond said cleats, seats on the body for engaging one end of each pin, and catches on the body for engaging the other ends of said pins. 45 50

3. In a box, a body, a lid for the body, having pins extending entirely across the same and permanently connected thereto, means on the body to receive one end of each pin, and spring-catches for engaging the opposite ends of said pins, the lid being notched adjacent to the free ends of the catches to thereby provide ready access to said catches. 55

4. In a box, a body, a lid for the body, posts in the body at the corners thereof, plates between the posts and the body at one side of the latter and having perforations, spring-catches between the opposite posts and the body, cleats upon the under side of the lid, and pins extending through the cleats and beyond the opposite ends thereof and one end of each pin being arranged to enter a perforation in a plate and the opposite ends of said pins being arranged for engagement by said spring-catches. 60 65 70

In testimony whereof I have hereunto set my hand in presence of two subscribing witnesses.

NATHANIEL B. LEAMAN.
